UNITED STATES PATENT OFFICE.

JOHN A. BODKIN, OF NEW YORK, N. Y.

TIE-PLATE AND RAIL ANCHOR.

Application filed July 15, 1920, Serial No. 396,451. Renewed September 8, 1924.

To all whom it may concern:

Be it known that I, JOHN A. BODKIN, a citizen of the United States, residing at the city of New York, borough of Manhattan, 5 in the county and State of New York, have invented certain new and useful Improvements in Tie-Plates and Rail Anchors, of which the following is a full, clear, and exact specification.

This invention relates to improvements in tie plates and rail anchors for use in connection with railroad construction, and has for its object to provide a device of this character which will be simple in construction and efficient in use.

Further, said invention has for its object to provide a device of this character in which the parts are so constructed that, when in use, the rail anchoring means will be prevented from becoming loosened.

Further, said invention has for its object to provide a device of this character in which there is a constant tendency for the rail anchoring means to be more firmly secured in 25 position when the device is in use.

Other objects will in part be obvious and in part be pointed out hereinafter.

To the attainment of the aforesaid objects and ends my invention consists of the 30 novel details of construction, and in the combination, connection and arrangement of parts hereinafter more fully described and then pointed out in the claims.

In the accompanying drawing forming 35 part of this specification, wherein like reference numerals refer to like parts,

Figure 1 is a plan showing a portion of a railroad track having applied thereto one form of a tie plate and a rail anchor constructed according to, and embodying my 40 invention;

Fig. 2 is an end elevation;

Fig. 3 is a side elevation;

Fig. 4 is a perspective view of the wedge;

Fig. 5 is an inverted perspective view of 45 the wedge, and

Fig. 6 is an end view of the wedge looking toward the head thereof.

Referring to the drawing 10 indicates a 50 tie plate provided with a plurality of holes 11 to receive spikes by means of which the plate 10 is secured to the tie 12. Extending downwardly from the under surface of the plate 10 are a plurality of longitudinally-extending, V-shaped ribs 13 adapted to be embedded within the tie 12 when the plate 10

is secured thereto, and serving to prevent the plate 10 from moving relatively to the tie 12.

Adjacent one of its sides, the plate 10 is 60 provided with an upwardly and inwardly extending lug 14 adapted to engage the base of the rail 15, and adjacent its other side the plate 10 is provided with an upwardly and inwardly extending lug 16 adapted to receive a wedge 17, the construction and purpose of which is hereinafter described. As shown, the inner wall of the lug 16, formed by the upwardly extending portion thereof, is inclined to the longitudinal axis of the 70 rail 15 in the direction of the line of travel, and the lower portion of the inner wall of the lug 16 merges with a recess 18 formed in the upper surface of the plate 10, and extending transversely thereof. The lug 16 75 is so proportioned and positioned that the inner portion of the inwardly extending portion thereof will overlie the base of the rail 15.

Extending upwardly from the plate 10 80 is a member 19 in line with the lug 16 and spaced therefrom in the direction of travel. The upper surface 20 of the member 19, is inclined upwardly with respect to the upper surface of the plate 10 in the direction of 85 the line of travel.

The wedge 17, which is preferably formed of malleable iron, comprises a head 21, and a body portion 22 adapted to be received within the lug 16, and to slidably engage 90 the recess 18 in the plate 10. The inner lateral surface of the wedge 17 is shaped to engage the upper and lower surfaces, and the edge of the base of the rail 15. At its end, the body portion 22 is provided with a thin 95 extension 23 adapted to engage the inclined surface 20 of the member 19 and to be bent upwardly thereby when the wedge 17 is placed in position, in order to lock the wedge 17 against movement. The body portion 22 100 is provided with a slit 24 extending throughout a portion of its length.

In use the tie plate 10 is placed in position upon the tie, 12, and the rail 15 is seated upon the upper surface thereof with one flange of its base engaging the lug 14 and the other flange of its base extending under the inwardly extending portion of the lug 16, and overlying the inner portion of the recess 18 formed in the upper surface of the plate 10. The tie plate 10 is then secured to the tie 12 in the usual manner, by driving spikes 110

through the holes 11. As the spikes are driven into place, the ribs 13, on the under side of the plate 10, will become embedded within the tie 12 and prevent the tie plate 10 from moving relatively to the tie 12. The wedge 17 is then driven into its operative position, within the housing formed by the lug 16 and the recess 18, by hammering upon its head 21, it being understood that the driving movement of the wedge 17 is in the direction of the line of travel. As the wedge 17 is driven into place, the thin extension 23 of the body portion 22 will engage the inclined surface 20 of the member 19 and will be bent upwardly, thus securely locking the wedge 17 against withdrawal. The inner surface of the wedge 17 will be forced into engagement with the upper and lower surfaces, and the edge of the base of the rail 15 thereby serving to hold the rail 15 against lateral movement.

When a train travels along the track, the rail 15 tends to creep in the direction of the travel thereof, and any movement of the rail 15 in this direction serves to force the wedge 17 more tightly within its housing, and more intimately into engagement with the base of the rail 15. On the rebound, there is a tendency for the wedge 17 to work loose by a rearward movement, but such movement is effectively prevented by reason of the fact that the extension 23 of the body portion 22 of the wedge 17 has been bent upwardly, as hereinbefore described.

It will thus be seen that, when the device is in use, there is a constant tendency to move the wedge 17 more firmly into its operative position, and that any possibility of the wedge 17 working loose is effectively prevented.

Having thus described my said invention what I claim and desire to secure by Letters Patent is:—

1. A device of the character described comprising a tie plate, lugs extending inwardly from the opposite sides thereof adapted to receive a rail, a tapering member adapted to engage with one of said lugs and provided with a longitudinal recess adapted to engage the upper and lower surfaces of the rail flange and the edge thereof intermediate said surfaces; said tapering member having a relatively thin overhanging portion extending longitudinally from one end thereof, substantially as specified.

2. A device of the character described comprising a tie plate, lugs thereon extending inwardly from the opposite sides thereof adapted to receive a rail, and a longitudinally-split tapering member adapted to engage, at its outer side, with one of said lugs, and provided along its inner side with a longitudinal recess adapted to engage the upper and lower surfaces of said rail flange

and the edge thereof intermediate said surfaces, substantially as specified.

3. A device of the character described comprising a tie plate, lugs thereon extending inwardly from the opposite sides thereof adapted to receive a rail, a longitudinally-split tapering member adapted to engage, at its outer side, with one of said lugs, and provided along its inner side with a longitudinal recess adapted to engage the upper and lower surfaces of said rail flange, and the edge thereof intermediate said surfaces and a member on said tie plate extending upwardly therefrom in the path of said tapering member adapted to be engaged by the free end of said tapering member, and to deflect the free end thereof, substantially as specified.

4. A device of the character described comprising a tie plate, lugs extending from the opposite edges thereof adapted to receive a rail, a transversely longitudinally-split member having its straight inner edge provided with a longitudinal recess adapted to engage with the upper and lower surfaces of a rail flange and the edge thereof intermediate said surfaces, and its outer edge arranged at an angle to said inner edge and adapted to engage with one of said lugs; the upper portion of said split member terminating in a relatively thin, flat end, and means on said tie plate, in the path of said split member, for deflecting the free end thereof by its engagement therewith, substantially as specified.

5. A device of the character described comprising a tie plate, lugs extending inwardly from the opposite edges thereof adapted to receive a rail, said tie plate having a recess therein extending under said rail flange adjacent to one edge thereof, a transversely longitudinally-split member arranged in the recess of said tie plate and having a straight inner edge provided with a longitudinal recess adapted to engage with the upper and lower surfaces of a rail and the edge thereof intermediate said surfaces, and its outer edge arranged at an angle to said inner edge and adapted to engage with one of said lugs; the upper portion of said split member terminating in a relatively thin, flat end, and a projection extending upwardly from said tie plate into the path of said split member for deflecting the free end thereof by its engagement therewith, substantially as specified.

Signed at the city of New York, in the county and State of New York, this 5th day of April, one thousand nine hundred and twenty.

JOHN A. BODKIN.
